United States Patent Office.

BENJAMIN D. STEVENS, OF DECORAH, IOWA, ASSIGNOR TO HIMSELF AND
CHARLES GILL, OF EXETER, NEW HAMPSHIRE.

Letters Patent No. 66,411, dated July 2, 1867.

IMPROVED MACHINE FOR FORMING SHEET-METAL PANS.

The Schedule referred to in these Letters Patent and making part of the same.

TO ALL WHOM IT MAY CONCERN:

Be it known that I, BENJAMIN D. STEVENS, of Decorah, in the county of Winneshiek, and State of Iowa, have invented an Improved Machine for Forming Bake-Pans, and other sheet-metal vessels of rectangular form; and I do hereby declare that the following is a full and exact description thereof, reference being had to the accompanying drawings, making part of this specification—

Figure 1 being a top view of the machine spread open ready for use.

Figure 2, a cross-section, showing the position of parts when the sheet metal is inserted ready to bend, and also after the bending is accomplished.

Like letters designate corresponding parts in both of the figures.

The machine has a central supporting-bar or bed-piece, B, which is secured to the bench of the workman. On one edge is hinged, by hinges *d d*, a clamp-bar or jaw, A, which is provided with a narrow groove, *a*, for the reception of the edge of the sheet of metal to be bent up into form. On the other edge of the bed-piece B is hinged, by hinges *g g*, a bending-bar or former, C, which is provided with a handle, D, for operating it. In addition to the clamp-bar A, for bending the sides of the vessel, there is a shorter, distinct clamp-bar, F, hinged by a hinge or hinges, *f*, to the same edge of the bed-piece, as shown, for bending the ends of the article; and there may be more than two clamp-bars, of different lengths, to suit different sizes of pans or other articles, all to be used in connection with the same former C; or the latter may be divided into different ones, to correspond with the different clamping-bars, but this is not necessary, while the use of the separator clamp-bars for the different lengths of the sides of the articles to be formed is essential with this instrument, since, after two opposite sides of an article are bent up, the clamp-bar for the other sides must pass between those already formed. The depth of the groove *a* in the clamp-bar is sufficient for the highest sides of articles to be formed. Then when a less depth is wanted, the proper gauge is determined by pins or screws *c c*, inserted into holes in the clamp-bar A, at different distances from the edge thereof, substantially as represented, for the edge of the metal to bear against. These gauge-pins *c c* may be used in connection with corresponding holes *b b* in the bed-piece, to keep the two parts firmly and exactly in place. Holes *b b*, in different positions, are used to correspond with the different positions of the gauge-holes in the clamp-bar A.

The sheet metal is inserted as indicated by the horizontal blue lines *x* in fig. 2, and then the forming-bar C is turned up, as shown by red lines in the same figure, thus bending the metal up as represented.

What I claim as my invention, and desire to secure by Letters Patent, is—

The combination and arrangement of the bed-piece B and the clamp-bar A and forming-bar C, hinged to said bed-piece on opposite sides thereof, substantially as and for the purpose herein specified.

I also claim hinging separate clamp-bars A and F to the same bed-piece B, for forming sides of different lengths, as herein set forth.

I also claim the gauge-pins *c c*, applied in combination with the grooved clamp-bar A for the purpose specified.

The above specification of my improved machine for forming bake-pans, and other sheet-metal vessels of rectangular shape, signed by me this fourteenth day of September, 1866.

BENJN. D. STEVENS.
